UNITED STATES PATENT OFFICE.

HAROLD H. KENNEDY AND THOMAS J. GIBBONS, OF INDIANAPOLIS, INDIANA,
ASSIGNORS TO THE WAVERLEY COMPANY, OF INDIANAPOLIS, INDIANA, A
CORPORATION OF INDIANA.

FOLDING CORNER-SEAT.

1,099,253.

Specification of Letters Patent.

Patented June 9, 1914.

Application filed August 16, 1912, Serial No. 715,457. Renewed April 13, 1914. Serial No. 831,653.

To all whom it may concern:

Be it known that we, HAROLD H. KENNEDY and THOMAS J. GIBBONS, citizens of the United States, residing at Indianapolis, in the county of Marion and State of Indiana, have invented certain new and useful Improvements in Folding Corner - Seats, of which the following is a specification.

This invention relates to improvements in folding corner seats, and while specially adapted for use in closed vehicles having a door hinged at the corner where the seat is located, it is not desired to limit its application to vehicle construction.

The object of the invention is to provide a seat with a back rest against both meeting walls of the corner, and in which the part opposite the door will be removed with the door when the latter is opened, to afford unobstructed passage through the door opening.

Another object is to provide a hinged seat adapted to be folded up out of the way, and to provide means operated by the seat, for positively locking the door and for keeping it locked while the seat is lowered for occupancy.

With these and other objects in view, the invention consists of certain novel features of construction and combinations of parts which will be hereinafter more fully described and pointed out in the appended claims.

In the accompanying drawings is shown the preferred form of our invention, in which—

Figure 1 is a corner portion of a closed vehicle with a hinged corner door, having our invention applied thereto in perspective view and partial vertical section of the vehicle body. Fig. 2 is a view of a like portion of the body in horizontal section showing the seat in top plan view with the door closed, and showing the open position of the door in dotted lines, and Fig. 3 is a vertical section on the dotted line 3—3 of Fig. 2.

4 is the floor of a closed vehicle body, 5 the front wall, and 6 a side door which is hinged to the front corner of the body by hinges 7 (see Fig. 2) adapting the door to be swung toward the front, to the position shown by dotted lines in Fig. 2, when opened. The door will be provided with

the usual latch (not shown), and in addition thereto it will be provided with a lock which is operated by the corner seat, as will be hereinafter described.

8 is the corner seat which is hinged to the front 5 by means of the hinges 9. The hinges 9 preferably have long straps 10 which are secured to the underside of the seat.

11 is a diagonal brace or support for the seat when the latter is in its lowered position for use. This brace comprises a lower tube which is hinged to the front 5 at 12 and a rod the lower end of which telescopes in the tube and the upper end of which is hinged at 13 to the bottom of the seat 8. The length of the tube is such as to permit the seat to be lowered only into proper position for comfortable occupancy, but in folding up the seat, as shown in Fig. 3, the rod will draw out of the tube thereby securing the additional length which the support requires.

Mounted under the floor 4 and supported by suitable hangers is a rock-shaft 14 having a front cranked end 15 which is hinged to the lower end of a vertical rod 16. The rod 16 passes through the floor 4 and terminates against the seat 8 when the latter is in its lowered position, and preferably in contact with a leaf 10 of the seat hinge in order to secure a solid bearing against the seat. Mounted on the rod 16 above the floor 4 is a collar 17 which is held at any given adjustment on the rod by a set-screw 18. Between the collar 17 and the floor 4 is a spirally wound spring 19 exerting a constant upward pressure on the rod 16. The pressure of the spring is adjusted by varying the height of the collar 17 on the rod 16. The rear end of the rock-shaft 14 is bent outwardly to form the crank 20, and this cranked end is hinged to a vertical bolt 21 which passes through the floor 4 immediately under the bottom of the door 6 when the door is in its closed position, and enters a socket 22 formed in the door for that purpose.

When the seat 8 is lowered to a position for use it depresses the rod 16 thereby rocking the shaft 14 in a manner to throw the bolt 21 up into the socket 22 in the door 6, and the door will be positively and securely locked as long as the seat is in position to be

occupied as such. This guards against any accidental opening of the door which might cause or permit the occupant of the seat to fall from the vehicle. As soon as the occupant rises from the seat so as to relieve it of his weight the spring 19 exerts sufficient pressure on the rod 16 to sufficiently draw the bolt 21 from socket 22 in the door 6 to unlock the door below and put it in condition 10 to be opened in the usual way.

The seat is provided with a back-rest which may be suitably upholstered, as shown, and which is divided on the line 23 into two portions 24 and 25. The part 24 is secured to the vehicle front 5, and the part 25 is secured to the door 6 and moves with the door when the latter is opened, as shown by dotted lines in Fig. 2, thereby removing it as an obstruction to passage in 20 and out through the door opening.

While we have shown the corner door as hinged at its front edge to the front door post, it may be hinged from its opposite or rear edge with substantially the same results so far as our invention is concerned, but this latter manner of hinging the door is not in accordance with the usual practice in vehicle construction because it swings the door back into contact with the rear wheel. 30 Instead of hinging the seat to the front wall of the vehicle and the movable back section to the door the seat may be hinged to the door and the back section above it secured to the door, and the remaining section of the 35 back secured to the front wall of the body, and while not quite as convenient with regard to the use of the seat, it is a practicable arrangement.

While we have described our invention 40 with more or less minuteness as regards details of construction and arrangement and as being embodied in certain precise forms, we do not desire to be limited thereto unduly or any more than is pointed out in the 45 claims. On the contrary we contemplate all proper changes in form, construction, and arrangement, the omission of immaterial elements and the substitution of equivalents, as circumstances may suggest or necessity 50 render expedient.

We claim:

1. A wall member, and a hinged door member in angular relation to the wall member when closed, a seat hinged to one of said 55 members, and a divided back support for the seat one part of which is secured to the door and the other part to the wall member.

2. The combination of a wall member, a door hinged to the wall member and occupying

an angular relation to the wall member 60 when closed, a seat hinged to one of said members, and a divided back support for the seat one part of which is secured to the door and the other part to the wall member.

3. The combination, with a corner seat, of 65 a door in the same corner, a two-part back-rest for the seat having one part secured to the door and moving with it and the other part secured to the wall cornering with the door.

4. The combination of two walls meeting 70 at an angle to form a corner, one of said walls having an opening at the corner, a door for said opening, a seat hinged to the opposite wall from the door and folding up 75 against the wall to which it is hinged, and a two-part back-rest one part of which is secured to the door and moves therewith and the other part is secured to the opposite wall.

5. The combination of two walls meeting 80 at an angle to form a corner, one of said walls having an opening at the corner, a door for said opening, a seat hinged to the opposite wall from the door and folding up 85 against the wall to which it is hinged, a two-part back-rest one part of which is secured to the door and moves with it and the other part is secured to the opposite wall, and means, operated by the seat when lowered, 90 to lock the door.

6. The combination of two walls meeting 95 at an angle to form a corner, one of said walls having a door-opening at the corner, a door for said opening, a seat hinged to the opposite wall from the door and folding up against the wall to which it is hinged, a two-part back-rest one part of which is secured to the door and moves with the door and the other part is secured to the opposite wall, means to limit the downward movement of the seat, and means controlled by the seat while in its lowest position to lock the door.

7. The combination of a wall member, a door member hinged to the wall member and 100 when closed occupying an angular relation to said wall member, a seat hinged to said wall member, and means operated by lowering the seat on its hinges to lock the door.

In witness whereof, we have hereunto set 11 our hands and seals at Indianapolis, Indiana, this 23d day of July, A. D. one thousand nine hundred and twelve.

HAROLD H. KENNEDY. [L. s.]

THOMAS J. GIBBONS. [L. s.]
